United States Patent Office

Des. 218,807

Patented Sept. 29, 1970

218,807

PACKAGING CARTON FOR FOOD OR THE LIKE

Herbert W. Rieke, Indianapolis, Ind., assignor to Inland Container Corporation, Indianapolis, Ind., a corporation of Indiana

Filed Mar. 2, 1970, Ser. No. 21,707

Term of patent 14 years

Int. Cl. D9—04

U.S. Cl. D9—231

Fig. 1.

Fig. 3.

Fig. 2.

Fig. 4.

FIG. 1 is a top plan view of a packaging carton for food or the like embodying my new design, the bottom thereof being identical to the top;

FIG. 2 is a side elevation thereof;

FIG. 3 is a side elevation thereof taken from 90° to the right of the side view of FIG. 2; and

FIG. 4 is a side elevation thereof taken from 45° to the right of the side view of FIG. 2.

I claim:

The ornamental design for a packaging carton for food or the like, as shown and described.
